UNITED STATES PATENT OFFICE.

LOUIS E. LANDES, OF LOS ANGELES, CALIFORNIA.

ELECTRIC SIGNAL FOR AUTOMOBILES.

1,086,600.

Specification of Letters Patent. Patented Feb. 10, 1914.

Application filed November 7, 1912. Serial No. 730,976.

To all whom it may concern:

Be it known that I, LOUIS E. LANDES, a citizen of the United States, residing at Los Angeles, in the county of Los Angeles and State of California, have invented certain new and useful Improvements in Electric Signals for Automobiles; and I do declare the following to be a full, clear, and exact description of the invention, such as will enable others skilled in the art to which it appertains to make and use the same.

This invention relates to signals, and more especially to those ordinarily employed at the rear end of automobiles and the like to indicate to the automobilist following the fact that the forward automobile is about to stop or is to turn to right or left; and the object of the same is to improve the construction of signals of this kind.

To this end the invention consists broadly in the provision of means whereby an electric current may be employed at night for illuminating the number signal and lighting the tail lamp as well as for illuminating the direction signal when desired, and by the provision of a manual switch mechanism the same electric circuit may be employed in the day time for actuating an index to point to the direction signal; and the invention consists particularly in the detailed structure for carrying out this idea and in an improved form of armature for moving the index to various positions—all as herein-after more fully described and claimed, and as shown in the drawings wherein—

Figure 1 is a rear elevation of the signal complete, showing it as connected by a cable with the setting mechanism which will be situated within reach of the driver. Fig. 2 is an enlarged rear elevation of the signal with its glass panels removed, and Figs. 3 and 4 are sections taken on substantially the lines 3—3 and 4—4 of Fig. 2. Fig. 5 is an enlarged elevation of the setting mechanism, and Fig. 6 a vertical section through the same just under the base plate, this view also illustrating the wiring. Fig. 7 is a vertical section through the setting mechanism similar to Fig. 6, without the wiring and excepting that the plate carrying the contacts has here been moved to the left whereas it was shown in Fig. 6 as set to the right for a purpose to appear. Figs. 8 and 9 are sections taken on substantially the lines 8—8 of Fig. 6; and Fig. 9 a section taken substantially on the line 9—9 of Fig. 8.

In the drawings I have conventionally illustrated the number N and an abbreviation S indicating the State as marked in white, light, or transparent characters on an otherwise opaque glass G secured within a frame F, so that the characters are lighted up or illuminated at night by the light I; and I have also indicated the tail light T as being in circuit with the illuminating light I and both connected up with a battery or some other source of electricity E carried at a convenient point on the automobile. In the day time it will obviously not be necessary to light the bulbs of the illuminating and tail lights, nor will it be desirable to illuminate the signals hereinafter referred to, and therefore I have devised mechanism for switching the current from the source of electricity through one of three magnets whose energization controls the movements of an index also located within the casing of this signal and which may therefore be made to point to one of the words of the movement signal forming part of the present invention.

Coming now more particularly to the details of the present invention, the casing 1 may well be shaped to carry both the day and night signals, and the direction signal 5 may well consist of the words "Left," "Stop," and "Right" painted on a clear glass pane of sector shape which is secured within a frame 3 and the latter in turn secured over the rear face of the casing in a manner which will be understood. These words I would dispose around the arc of the sector as shown in Fig. 1, each over a compartment, and the various compartments within the casing are produced by a transverse curved partition 4 and two radial partitions 5 forming three boxes or chambers, within each of which is an electric bulb standing respectively behind the word constituting the signal; while the same pane 2 of glass may extend downward over the tail light T and the latter therefore shines through it in the night time. By preference, however, I would have the frame 3 covering this part of the mechanism distinct from the frame F which carries the number, et cetera, because in selling the device to the automobilist it is contemplated that he shall remove the frame F and insert a panel G having the proper number N and State abbreviation S, whereas it is not intended that he shall remove the frame 3 and pane 2 un-

less he needs to gain access to the signal mechanism. Across the frame 3 behind the glass 2 I secure a shield 6, preferably cut from metal in the shape of an arrow-point, 5 and made slightly larger than the index to be referred to hereinafter, and by preference this shield is disposed in such position that it stands between two of the words and does not cover any of them.

10 For convenience in the following description I will number the bulb and therefore the signals 7, 8 and 9 in Figs. 2 and 6, and I will letter the other two bulbs in Fig. 6 as T and I to correspond with the tail and 15 illuminating bulbs shown in Fig. 2.

I might here throw out the suggestion that the glass panel 2 over the three words around its arc could be painted in three contrasting and vivid colors, leaving the 20 strokes of the several letters clear or white, as for instance red over the intermediate panel indicating "Stop," and blue over one of the other words and yellow over the remaining word; and if this system were followed in any city and became generally understood, a chauffeur who possibly could not 25 read would soon learn to read the signals by their colors. However, this detail need not be illustrated or further amplified, as 30 is only a suggestion.

With the above construction, at night when the electric circuit is switched onto the wires leading to the various bulbs, the tail light T burns constantly, the illuminating 35 light I also burns constantly behind the number plate, and the other three bulbs will not burn and therefore no word is displayed above the tail light unless the current is switched through one or the other of said 40 bulbs in a manner yet to be described. In the day time, however, it is not advisable to use a direction signal which must be illuminated, and I therefore prefer the following construction. Pivoted at 10 within the casing 45 1 is an index 11 of a size and shape adapted to be completely concealed by the shield 6, and connecting the shank of this index with the pivot is a spring 12 which is of sufficient strength to hold the light index normally at 50 the angle shown in Fig. 2 where it is concealed behind the shield as indicated in dotted lines in Fig. 1 but which will permit said index to be moved in either direction when desired. The bracket 13 which carries the 55 pivot pin 10 is secured to the back of the casing and carries a second pin 14 whereon is pivotally mounted an armature of peculiar shape which I employ in this connection. The same comprises a soft-metal plate 60 15 turned up at one edge as at 16, having an ear 17 at one end pivoted on said pin 14, and having an upstanding arm 18 at its other end connected pivotally by a short link 19 with the shank of the index 11. 65 Three electro-magnets coact with this armature,

two of them numbered 27 and 29 being secured within the casing below opposite edges of the plate 15, and a third one numbered 28 being secured within the casing with its core standing just beyond the upturned edge 16 of the plate—all as best seen in Fig. 2. With the parts standing as therein shown (when the index 11 will be hidden behind the shield 6 as understood) if the current be sent through the magnet 27 70 the armature will be tilted on its pivot so that its arm 18 will draw on the link 19 and the index will be moved to the left and over the word "Left," but if the magnet 29 be energized the plate 15 will be tilted in the 75 opposite direction and the link will cause the index to move to the extreme right over the word "Right." If, however, neither of these magnets is energized, but the current is switched through the magnet 28, the upturned edge 16 of the plate 15 will be attracted so that the plate will be turned to about a horizontal position and its arm 18 will extend straight upward, with the result 80 that the link 19 will swing the index so that it will point to the word "Stop." In any case, as soon as the current is cut off, the spring 12 restores the index to the position shown in this view when it is again hidden behind the shield 6; and, if the index is painted white or perhaps enameled in 85 white as I would prefer, and the face of the shield is painted black, the automobilist following behind this signal sees nothing but the three words exposed in the daylight 90 or at dusk but is instantly attracted when a white index appears in sight and points to one of them. At night of course he would see none of these words so long as the lamps 7, 8 and 9 are not lighted. 95

An important feature of my invention 100 consists in the specific construction of the setting mechanism which will be mounted on the dash board or somewhere within easy reach of the driver of the automobile, and its details of construction are well illustrated in the drawings on Sheet 2. The casing 30 contains a three-fingered plate 31 connected through a wire 26 with the battery E, and its fingers carry buttons 32, 33 and 34, projecting through the face plate of the casing respectively opposite the words "Left," "Stop," and "Right," which are inscribed thereon as shown in Fig. 5. Beneath and out of contact with said plate the 110 casing also contains a slideable member, preferably comprising an insulated strip 35 having slots 36 moving over headed pins or screws 37, and the strip also carries a knob 38 projecting through a slot 39 in the face-plate of the casing between the words "Day" and "Night" so as to indicate in 115 what position the strip is set when the knob is moved to either extreme of the slot 39. Said strip 35 carries rather wide contact 120 125 130

tongues 40, 41 and 42 whose bodies, when the strip is adjusted, move beneath the inner ends of the push buttons 32, 33 and 34 as indicated by their two positions in Figs. 5 6 and 7, but whose free extremities or tips make contact respectively with upturned points 43 at the inner extremities of three binding posts 44, 45, and 46 which are respectively connected by branch wires 47, 48 and 49 with the lamps 7, 8 and 9 as seen in the diagrammatic view, Fig. 6. Or, when the plate 35 and its tongues are moved to the left as indicated in Fig. 7, the tips of said tongues make respective contact with 15 the points of three other binding posts 51, 52, and 53, with which are respectively connected branch wires 21, 22 and 23 leading respectively to the electro-magnets 27, 28 and 29, beyond which a common return wire 20 24 leads through the wire 25 back to the battery E. The return wire of the lamp circuit is indicated at 54, leading back to the wire 25 and thence to the battery E, but this return wire 54 also serves as the return wire 25 from the tail lamp T and the illuminating lamp I. For the purpose of lighting the last-named lamp, the plate 31 carries a depending spring tongue 55 at one extremity and the strip 35 carries a spring tongue 56 30 adapted to move under and make electrical contact with said tongue 55 when the strip is moved to the right as seen in Fig. 6. Directly beneath the spring tongue 55 but out of contact therewith is a point at the inner 35 end of a binding post 57, from which a wire 58 leads through the tail light T and thence through the illuminating light I and is connected with the common return wire 54 above described. With this construction it 40 follows that when the strip 35 and all its tongues is moved to the right as for use of the signals in the night, the spring tongue 56 comes between the spring tongue 55 and the point at the inner end of the 45 binding post 57 and closes a circuit through these elements and hence completes the circuit from the battery E through the tail light T and illuminating light I, and back through the wires 54 and 25 to the battery, 50 with the result that these lights burn constantly.

When now the driver wants to indicate that he will stop, he pushes the button 33 and a circuit is closed through the intermediate tongue 41, the binding post 45 and branch wire 48, the intermediate lamp or bulb 8 behind the word "Stop," and the common wire 54 back to the battery; and if the driver should desire to indicate that he will 55 turn to the left or to the right he has but to push the proper button to display the proper signal at the rear of the automobile. In the daytime, however, the knob 38 is moved to the left in the slot 39 and this carries the 60 various tongues to the position shown in

Fig. 7. Assuming now that the driver wishes to indicate that he proposes to turn to the left, he pushes the left hand button 35 which completes a circuit from the battery through the tongue 40, binding post 51, 70 branch wire 21, magnet 27, and common wire 24 back to the battery; and the energization of the magnet 27 tilts the armature on its pivot 14 and through the instrumentality of the link 19 turns the index 11 to the 75 left so that its tip points to the word "Left." In a like manner he could indicate that he will turn to the right or proposes to stop, by simply pushing the proper button.

Thus it will be seen that this improved 80 automobile signal is useful in daytime or nighttime, by the proper adjustment of the knob 38, that when adjusted for the night time the same circuit lights up the tail lamp and illuminates the number (although of course these features could be omitted if desired), and that when used in the day time no electricity flows through the device except when the driver desires to make use of his direction signal. Moreover, the direction is indicated at night by an illuminated word, it is indicated in the day time by a white hand moving out from under a dark shield so as to come into sight of those who follow, and the shift from one system to the other is made by the driver without leaving his seat and simply by pushing the knob 38 in the proper direction. It is quite possible that the entire lighting system of the automobile could be put into circuit with the tail lamp T, as shown at H in Fig. 6, so that movement of the knob 38 to the right would light up the automobile as the law requires and its movement to the left would extinguish all lights on the machine. 105

What is claimed as new is:

1. A circuit closer for signal systems comprising a casing, a plate fixed thereto and having three fingers, three buttons whereof each has its shank connected with one finger 110 and its head standing on the exterior of the casing, two series of points located within said casing and with their respective members arranged in pairs the members of which are adjacent each other and each pair 115 comprising one point from each series and said points being connected with separate instrumentalities, the inner end of each button-shank standing above the space between a pair of said points, an insulated strip 120 mounted within said casing and having means on its exterior whereby it may be slid to either extreme position, and three contact tongues carried by the strip, each having a wide body standing beneath the inner end of a button-shank in either position of the strip and a narrow tip in contact with one of said points, the whole acting substantially as described. 125

2. The combination with two series of 130

points having their respective members standing adjacent each other, and a series of push buttons with their shanks standing respectively over the pairs of adjacent points; 5 of a series of spring tongues insulated from each other and each having a wide body disposed beneath one of said button shanks and a reduced tip adapted to make contact with one of said points, and means for setting the series of tongues manually with their tips registering with the points of either series.

19 3. The herein described electric switch comprising a casing, two series of upstanding points therein disposed with the corre- 75

sponding points of the different series side by side, a plate within the casing having spring fingers whereof each stands above a pair of the points, and a manually slideable member having tongues standing respectively beneath said fingers and adapted to be set above the points of either series, for the purpose set forth. 20

In testimony whereof I have hereunto set my hand in presence of two subscribing 25 witnesses.
